(57) **CLAIM**

We claim the ornamental design for a model tank suspension, as shown and described.

DESCRIPTION

FIG. 1 is a perspective view of a model tank suspension, showing our new design;

FIG. 2 is a top plan view thereof;

FIG. 3 is a bottom plan view thereof;

FIG. 4 is a right-side elevational view thereof, the left-side elevational view being a mirror image thereof; and,

FIG. 5 is a front elevational view thereof, the rear elevational view being a mirror image thereof.
